WOOD CONDUIT

Neal T. MacKenzie and Harry E. Hall, St. Paul,
Minn., assignors to General Timber Service,
Inc., St. Paul, Minn., a corporation of Delaware

Application October 1, 1941, Serial No. 413,182

6 Claims. (Cl. 138—78)

It is an object of our invention to provide a novel conduit having a multiplicity of narrow wood staves connected together by flexible metal binding members and so arranged that the structure may be shipped in compact form and erected with a minimum of skill and labor.

Another object is to provide a conduit of this class with a novel arrangement of binding and tensioning devices whereby the binding members may be fastened and placed under high tension quickly and easily.

Further objects are to provide low cost wood culverts and pipes of large diameter and to facilitate the handling of such conduits by furnishing them in short, collapsible sections adapted to be erected and fit together end to end with tight telescoping joints.

Other objects will appear and be more fully pointed out in the following specification and claims.

Referring to the accompanying drawings:

Figure 1 is a side elevation view showing a unit of our improved conduit;

Fig. 2 is a partial end view and partial cross section of the same on a larger scale;

Fig. 3 is a side view of one our wire anchoring and tensioning devices;

Fig. 4 is an end view showing the unit rolled in a compact form for shipment and easy handling;

Fig. 5 is a full size, fragmentary cross section showing one of our anchoring and tensioning devices in operative relation to the adjoining staves;

Fig. 6 is an elevation of one of the staves as viewed from an edge thereof;

Fig. 7 is a detail plan view of one end of one of the binding wires, and

Fig. 8 illustrates an alternate form of end joint, a pair of the adjoining staves being shown in side elevation.

Our improved conduit comprises a multiplicity of wood staves 8 which should not be less than about one and one half inches thick, three inches wide and of a length which may be handled with ease. For conduits of inside diameter up to 24 inches, four foot lengths are preferred. The cost of material is reduced by utilizing standard framing lumber stock in which case the inner and outer surfaces of each stave are parallel to each other. The side edges are shaped to converge radially inward toward the axis of the conduit and each stave is formed along its longitudinal edges respectively with a rounded tongue or bead 9 and a similarly shaped

groove so that the edges of each stave interlock with those of the adjoining staves. The outer corners of each stave are beveled, as indicated at 10 (Figs. 2 and 6) and the ends are rabbeted to form on each stave an exterior tapered surface 11 at one end and an interior complementary surface 12 at the other end, permitting the units or sections of the conduit to fit together in telescoping relation end to end. The several staves are preferably impregnated with a preservative of the toxic type, such as creosote.

Extending across the exterior surface of each stave is a plurality of narrow grooves 13 to receive binding wires 14. The grooves 13 for each wire are aligned circumferentially of the conduit to coact with the wires in aligning the ends of the staves when the conduit is erected. One of the staves 8a of each unit is provided with a wire tensioning and anchoring device 15 for each wire 14. As best shown in Figs. 3 and 5, the anchoring devices 15 comprise cap screws having heads adapted to be turned by a wrench and cylindrical shanks 16 which are drilled transversely to provide a hole 18 in each adapted to receive an end 14a of a wire 14. A screw-threaded portion 17 of each cap screw is threaded in the stave 8a in alignment with a wire in the grooves 13 and a large countersink 8c is formed around the screw to receive a coil of the wire end 14a. The ends of the wires 14 opposite the ends 14a are formed with loops 14b (Fig. 7) to embrace the shanks 16 of the cap screws. For conduits up to two feet in diameter type B212 telephone line wire may be used as the binding wires 14, such line wire being made of a rust-resistant steel alloy having the proper degree of flexibility and adequate strength. Where the wires 14 cross each stave they are confined in the grooves 13 by pairs of staples 19.

In our alternate form of end joint, illustrated in Fig. 8, each stave 8b has at one end a tapered surface 11a formed with a bead 20 projecting outward and extending across said surface to fit into a similarly formed groove in the overlying surface 12a of the adjoining stave 8b. The staves 8b are otherwise constructed like the staves 8, with tongues and grooves along their side edges and grooves 13b to receive binding wires. They may be bound together and placed under radial compression by the wires 14 and devices 15.

In the manufacture of our conduits, assuming that the several staves for a unit have been shaped as hereinbefore described, one of the staves 8a for each unit is formed with the coun-

tersinks 8c and fitted with a number of the anchoring and tensioning devices 15, one in alignment with each of the grooves 13. The wires 14 are attached by passing the shanks 16 of the cap screws respectively through the end loops 14b of the wires. The correct number of staves to form a unit are placed, edge to edge, on a flat surface with the stave 8a along one margin of the group which is preferably held in a suitable jig. The wires 14 are now placed straight across the group from the anchoring devices and are confined in the grooves 13 by driving pairs of the staples 19, leaving the ends 14a of the wires projecting from one edge of the group.

The flat, flexible unit thus formed is finally removed from the jig and is ready for shipping either in the form of a flat mat or in a roll, as indicated in Fig. 4. It will be understood that such reverse rolling produces a compact bundle which may be handled with ease by one man. Either the stave 8a or the one at the opposite margin of the mat may be placed at the center of the roll.

When the rolled or flat units have been delivered at the site where they are to be installed, the operation of erecting the conduit may be accomplished quickly and easily. To erect a unit starting from the rolled form shown in Fig. 4, it is merely unrolled and then bent in the reverse direction so that the wires 14 encircle the exterior of the staves while the rounded tongues 9 are seated in the similarly shaped grooves by rolling action. With the staves forming substantially a cylindrical tube, the ends 14a of the wires are inserted in the holes 18 of the cap screws 15 and then these screws are turned in by the use of a suitable wrench applied to the heads of the screws. The end portions 14a of the wires are thereby wound on the shanks 16 until the wires 14 have been placed under a suitably high tension. Friction of the threads 17 in the staves 8 is sufficient to retain the wires under tension. The countersinks 8c conceal and confine the coils of wire on the shanks 16 and coat with cap screws in affording a large range of adjustment.

With the alternate form of end joint shown in Fig. 8, after erecting one section, the succeeding section must be closed around the projecting bead 18 of the first completed section and then fastened by connecting the binding wires to the cap screw and turning the latter to produce adequate tension. Such closing of the sections around the ends of those previously erected is unnecessary with the construction illustrated in Figs. 1 to 6, inclusive. Sections having the plane, exterior tapered surfaces 11 at one end and similar interior surfaces 12 at the other end may be erected independently of each other and then slipped into telescoping relation to each other, end to end, to form a conduit of any desired length. Ordinarily when our conduits are used under ground, as when used as culverts, no fastening is required to prevent longitudinal separation of the sections. When so used, our improved conduits have great strength to resist the pressure of the earth on the outside tending to crush or distort the tubular shape and unusually tight joints are maintained. The beads 20 retain the sections against longitudinal separation and produce a tighter end joint which has advantages when the conduit is used above ground or where internal hydraulic pressure is a factor. Our invention may be used to advantage for culverts of various sizes, for salt

water and chemical conduits and in numerous other situations where light weight and the other peculiar characteristics of wood are needed.

Having described our invention, what we claim as new and desire to protect by Letters Patent is:

- 5 1. A conduit comprising a multiplicity of wood staves shaped to fit together edge to edge to form a pipe, flexible wires extending across the exterior surfaces of said staves and a screw threaded in a 10 stave in alignment with each of said wires, each screw having a tapered and threaded inner end portion engaging a stave and opposite ends of each wire being connected to one of the screws and said screws being arranged to tension the several wires when turned inward.
- 15 2. A conduit comprising a multiplicity of wood staves having side edges adapted to fit together edge to edge, longitudinally spaced grooves being formed in the exterior surfaces of said staves to receive binding members, flexible binding members extending across the staves in said grooves, one end of each of said members being anchored on one of said staves, means fastening the several staves to said members whereby the staves are joined together as a flexible mat adapted to be rolled spirally in a compact bundle and means adapted to severally tension the binding members upon the exterior of the staves when in tubular form.
- 20 3. A conduit comprising a multiplicity of wood staves formed with interlocking side edges adapted to fit together edge to edge as a pipe, flexible binding wires extending across the staves, means fastening the several staves to said wires, whereby the staves are joined together as a flexible mat and a screw threaded in a stave in alignment with each of said wires, the several screws having perforated shanks projecting substantially radially from the exterior of the conduit, one end of each of said wires being formed with a loop embracing the shank of one of said screws and the other end of each wire being insertable in the perforation in a shank of a screw and being adapted to be wound thereon to tension the wires on the exterior of the staves when erected as a tubular shell.
- 25 4. A sectional conduit comprising, a plurality of groups of wood staves, the staves of each group being shaped to fit together edge to edge as a pipe section, flexible metal binding members extending across the exterior of the staves of each group, a tensioning device connecting the ends of each binding member together to compress the staves radially inward, longitudinally tapered interior surfaces formed on the ends of the staves of one section and complementary tapered surfaces formed on the exterior end portions of the staves of the other section to fit in telescoping relation within the first mentioned section, said tensioning devices being operable to press the interior tapered surfaces upon said complementary surfaces.
- 30 5. A sectional conduit comprising a plurality of groups of wood staves, the staves of each group being shaped to fit together edge to edge as a pipe section, flexible binding members extending across the exterior of the staves of each group, means for tensioning the several binding members upon the staves of each group and projecting members formed on end portions of the staves of one section to fit in interlocking, telescoping relation to complementary surfaces formed on the end portions of the staves of the other section whereby said sections may be secured end to end.

against longitudinal separation, said binding members and tensioning means being operable to contract the staves of one section into interlocking engagement with those of the other section.

6. A conduit comprising a multiplicity of wood staves shaped to fit together edge to edge to form a tubular structure, flexible wires extending across the exterior surfaces of said staves and means for tensioning said wires comprising a screw threaded in a stave in alignment with each 10

5 of said wires, said screws having tapered and threaded inner end portions and being formed to engage an end of a wire and to be turned inward to wind the wire thereon for placing it under tension and the staves being formed with countersink recesses to receive the portions of the wires which are wound on the screws.
